UNITED STATES PATENT OFFICE.

WILLIAM J. CARDWELL, OF OWOSSO, MICHIGAN, ASSIGNOR OF ONE-FIFTH TO R. STANLEY DAY, ONE-TENTH TO CLAUDE C. DAY, ONE-TENTH TO LEONARD A. HALL, AND ONE-TENTH TO ARTHUR DURR, ALL OF OWOSSO, MICHIGAN.

AUTOMATIC RAILROAD GRADE-CROSSING SIGNAL.

Application filed April 28, 1928. Serial No. 273,563.

The present invention relates to a railroad grade crossing signal and has for its prime object to provide a structure which is automatically operated by the train to eliminate the danger of grade crossing accidents as far as possible and to reduce the toll of human life at such grade crossing accidents.

Another very important object of the invention resides in the provision of an automatic railroad grade crossing signal of the class described which is simple in its construction, strong and durable, inexpensive to manufacture, may be installed without disturbing the roadbed and may be maintained at low cost, and will prove thoroughly efficient and reliable in its operation.

With the above and numerous other objects in view as will appear as the description proceeds, the invention resides in certain novel features of construction, and in the combination and arrangement of parts, as will be hereinafter more fully described and claimed.

In the drawings:

Figure 1 is a top plan view of the railroad grade crossing showing my improved signalling means associated therewith,

Figure 2 is a detail vertical section through the lower portion of the signal post,

Figure 3 is an enlarged detail section taken substantially on the line 3—3 of Figure 1,

Figure 4 is an enlarged detail section taken substantially on the line 4—4 of Figure 1,

Figure 5 is an enlarged transverse detail vertical section taken substantially on the line 5—5 of Figure 4,

Figure 6 is an enlarged detail vertical longitudinal section taken substantially on the line 6—6 of Figure 1,

Figure 7 is a sectional view taken substantially on the line 7—7 of Figure 8,

Figure 8 is a detail elevation of the upper portion of the signal post showing the signal arm,

Figure 9 is a horizontal section taken substantially on the line 9—9 of Figure 8,

Figure 10 is a transverse horizontal section taken substantially on the line 10—10 of Figure 3,

Figure 11 is an enlarged detail section taken substantially on the line 11—11 of Figure 1,

Figure 12 is a sectional view taken substantially on the line 12—12 of Figure 3, and

Figure 13 is a detail elevation of a modified form of the train actuated mechanism.

Referring to the drawing in detail it will be seen that the numeral 5 denotes the rails of a railroad track and the numeral 6 a grade crossing such as the roadway or the like. A signal post disposed in one corner formed by the track and the roadway a suitable distance from the adjacent rail of the track as indicated to advantage in Figure 1 and this post comprises a hollow column 7 rising from and communicating with a casing 8.

A pair of fixed signal arms 9 are mounted on the upper end of the column 7 to incline downwardly therefrom at an angle of approximately forty-five degrees and have preferably written thereon the word "Caution". The bottom edges of the arms 9 are partially covered by a bottom 9'.

A rockable signal arm 10 extends through openings 11 in the top of the column and is of conventional construction having the word "Stop" thereon and having one end provided with transparent signalling elements 12 to straddle a source of light 14.

Normally the signal arm 10 is in a position between the signal arm 9 so as not to be visible and rests on the bottom 9'. A bracket 15 rises from the bottom of the casing 8 and has rockable therein a bell crank lever 16, to one end of which is pivoted as at 17 or otherwise suitably mounted, a rod 18, the other end of which is offset as at 19 to extend through a slot 20 in the upper portion of the column.

The signal arm 10 is provided with a lateral projection 21 with which the upper extremity of the offset portion 19 may engage for lifting or swinging upwardly the signal arm 10 to the signalling position as shown in Figure 8.

A bracket 23 rises from the bottom of the casing 8 and has rockable therein a bell crank 24 and to one end of which is pivoted as at 25 or otherwise mounted, a rod 26 extending up through the column and having an offset end 27 or the like projecting through a slot 28 in the column and the extremity of this offset portion 27 is adapted to engage the other projection 21 for holding the signal arm 10 in signalling position as will be more apparent as the description proceeds.

An operating bar 30 is disposed along the outside of one of the rails 5 to one side of the roadway 6 at any desired distance therefrom

and a similar operating bar 31 is mounted alongside the same rail 5 to the other side of the roadway.

The bars 30 and 31 are sufficiently long so that one car is on them at all times. Both of these operating bars are mounted to slide between said rails 5 and the guides 32. These guides 32 have springs 33 mounted therein urging the operating bars upwardly to project slightly above the ball of the rail and short teeth 34 are provided on the operating bars to limit their upward movement by engaging underneath the ball of the rail as is indicated in Figure 10.

15 The operating bars are each provided with a pair of rack bars or the like 35 depending therefrom one to each side of the center guide and meshing with the pinion 36. In the illustration of the invention as contemplated by 20 Figure 1 wherein the train is represented as travelling in the direction of the arrow 37, the rack bars 35 to the left end side of the rail of the roadway 6 engage the pinions 26 at their right side as indicated in Figure 11.

25 Therefore as the train travels in this direction and is on or over the operating bar 30, the stop signal is actuated and remains in this position until the train or engine is upon the release and operating bar beyond or just over 30 the crossing in the direction the train is travelling and the train or engine upon this bar unlocks the signal arm 10 and also pulls rod 73, pushing up rod 19 and holding the signal arm 10 in the position until the train or 35 engine is off the release and operate the bar then the signal arm goes back to normal, to be hid between the caution blades or arms 9.

The rack bars 35 however to the right hand side of the roadway 6, engage their respective pinions 36 to the left as is indicated in 40 Figure 3. The purpose of these features will appear as the description proceeds.

An elongated casing 38 is mounted alongside of the operating bar 30 as indicated to 45 advantage in Figure 1 but particular attention to Figure 6 where it will be seen that a shaft 39 is journaled through one side of the casing 38 and one of the pinions 36 is fixed thereto at the outer end of the shaft.

50 On the inner end of the shaft 39 is formed a crank 40 to which is pivoted as at 41 a bar 42 guided to move up and down in an opening 43 in the guide plate 44. The bar 42 is provided to the left of the plate 44 with an opening 45. A rod 46 is slidable through an opening 47 in the right hand end of the casing 38 and is slidable through openings 48, in the ends of the casing 8 and an intermediate portion of the rod 46 is pivotally engaged as at 55 49 to the bell crank lever 16.

The end of the rod 46 in the casing 38 is pivoted as at 50 a catch 51 extending through the slot 52 in the upper portion of the plate 44 and having an offset end 53 en-

gageable in the hole 45. A shaft 55 is journaled through the inner side of the casing 38 and has the other pinion 36 of the operating bar assembly 30 mounted thereon and the inner end of this shaft is formed with a crank 56 having an offset terminal 59 engageable under the catch 51.

65 Referring to Figure 6 it will be seen that the shafts 39 and 55 always rock in a clockwise direction when the operating bar 30 is released. Attention is now directed to Figures 3 and 4. The numeral 58 denotes a casing located alongside the release and operating bar 31 and having shafts 59 and 60 journaled to one side thereof with the pinion 36 thereon actuated by the rack bars 35 of the 70 operating bar 31.

75 Both of these shafts 59 and 60 rock in a counter clockwise direction when the operating bar 31 is depressed. A rod 46 is slidable through an opening 61 in the left hand end of the casing 58 and is pivotally engaged as at 62 with a catch member 63 in the form of a rod offset intermediate its ends to provide a shoulder 64 engageable with an abutment 65 depending from the top of the casing 58.

80 A spring 66 is anchored high enough to have an upward pull on the right hand of the casing and is engaged with the right hand end of the catch rod 63 and normally holds the parts so that the shoulder 64 is disengaged 85 from the abutment 65. A crank 67 is provided on the inner end of the shaft 60 and has an offset terminal 68 engageable with the catch rod 63 for dislodging its shoulder 64 from the abutment 65 as will appear later in 90 the description.

95 The shaft 59 is provided with a crank 69 which is pivotally engaged as at 70 with a link 71. This link 71 is pivotally engaged as at 72 with a rod 73 slidable through the opening 61 and pivotally engaged as at 74 with the bell crank lever 24.

100 The rod 73 is slidable through the right hand wall opening 48 of the casing 8. It is thought that the details of construction have 105 been described sufficiently and now follows the operation.

Assuming that a train is approaching from the left it will be seen that the first wheel will depress the left hand end of the operating bar 30 and thereby actuate the shaft 39 causing the crank 40 to swing in a clockwise direction and pull the bar 42, the catch 51 and the rod 46.

115 The rod 46, of course, rocks the bell crank lever 16 and pushes upwardly on the rod 18 so that the signal arm 10 is swung in the position shown in Figure 8. Now that the rod 46 is pulled, the catch 63 will also be pulled so that its shoulder 64 engages with the abutment 65 so that the signal arm 10 is held in a signalling position and the train moves over the remaining portion of the trip bar 30 and

the shaft 55 will be rocked to swing the crank 56 in a clockwise direction and raise the catch 51 and release bar 42.

When the front wheels of the train depress the left hand end of the trip bar 31, the shaft 59 is rocked in a counter clockwise direction thereby pulling upon the link 71 and the rod 73 to the right and rocking the bell crank 24 in a clockwise direction so as to push upwardly on the rod 26 so that the upper end of said rod 26 will hold the arm 10 in a raised position.

As the train progresses further and depresses the right end of said bar 31, the shaft 60 will rock in a counter clockwise direction and the crank 67 will disengage the catch 63 from the abutment 65 and the spring 66 will pull the catch 63 to the right and also the rod 46 to the right thereby rocking the bell crank 16 in a clockwise direction and pulling down on the rod back to normal position but this will not affect the signal because it is being now held by the rod 26.

When the train passes completely off the bar 30, the crank 56 will swing in a counter clockwise direction and allow the catch 51 to engage the opposite end 53 by gravity on the bar 42 and said bar 42 will be moved to its normal position in Figure 6 by the bell crank 40 swinging in a counter clockwise direction so that the said end 53 will engage in the hole 45 ready for the next train.

It will also be seen that the crank 69 will swing in a clockwise direction to cause the rod 26 to be lowered thereby allowing the signal arm 10 to be lowered between the signal arms 9. If the train goes in the opposite direction over crossing 6, the crank 60 will be rocked but will be an idle element. The crank 59 would be rocked and would cause the raising of the signal arm 10 as will be readily understood and then as the same reaches the operating bar 30 the crank 6 would be rocked to raise the catch 51 so that the crank 40 and bar 42 would become idle elements.

In Figure 13 I have shown a modified form of the operating bar mechanism, the bar being indicated by the numeral 31' and having a pin and slot connection 100 with a bell crank 101 which is connected with a link 102 engaged on a crank 103 and arranged to the shaft 59.

A link 104 is engaged with the bar 31' and with crank 105 on the shaft 60. It will be seen that this operating bar structure operates to the same advantage as that previously described.

It is thought that the construction, operation and advantages of the invention will now be quite apparent to those skilled in this art without a more detailed description thereof.

The present embodiment of the invention has been disclosed in detail merely for the purposes of exemplification since in actual practice it attains the features of advantage

enumerated as desirable in the statement of the invention and the above description.

It will be apparent that changes in the details of construction, and in the combination and arrangement of parts may be resorted to without departing from the spirit or scope of the invention as will be hereinafter claimed or sacrificing any of its advantages, as having one or more signal posts connected to by operating journals to both sides of the track, journaled to run under the track, or a single post to be in the center of the highway or to either side of the highway.

Having thus described my invention, what I claim as new is:

1. In a signal, a hollow column, a signal arm rockable through an opening in the top of the hollow column, a pair of rods slidable in the hollow column and having offset upper ends extending through slots in the column, said signal having lateral projections with which the upper ends of the rods are engageable.

2. In a signal, a hollow column, a signal arm rockable through an opening in the top of the hollow column, a pair of rods slidable in the hollow column and having offset upper ends extending through slots in the column, said signal having lateral projections with which the upper ends of the rods are engageable, a casing on which the hollow column is mounted, bell cranks in the casing, one connected with each rod, and means for swinging the bell cranks.

3. In a signal, a hollow column, a signal arm rockable through an opening in the top of the hollow column, a pair of rods slidable in the hollow column and having offset upper ends extending through slots in the column, said signal having lateral projections with which the upper ends of the rods are engageable, a casing on which the hollow column is mounted, bell cranks in the casing, one connected with each rod, and means for swinging the bell cranks, and means for holding the bell crank to the position to which they are swung by said means, means for swinging the other bell crank, and means for then releasing the second mentioned means.

4. In a railroad grade crossing signal, a pair of spaced operating bars actuatable by the wheels of a train, a pair of rock shafts for each operating bar, means operatively connecting the bars and the shafts, a crank on one of the shafts of one of said pair, first operated by one of the bars in the travel of the train on the track, a bar engaged with the crank, means slidably mounting the second mentioned bar, said second mentioned bar having a hole, a signal operating rod, a catch engaged with the rod and engageable with the hole, a signal, signal operating means therefor, means operatively connecting the signal operating means and the rod so that when said one of said operating bars is

first engaged by the wheel of the train, said rock shaft is rocked to swing the crank and pull the second bar and rod to cause the operation of the signal, a second catch 5 on the rod, and an abutment with which the second catch is engaged when the rod is pulled, a spring for returning the second catch when the train is off said one operating bar, a second one of the shafts of said 10 pair operated by said one operating bar after operation of said first shaft of said first mentioned pair, one of the shafts of the other pair being actuatable by the other operating bar, a crank on said one shaft of said 15 last mentioned pair, a rod connected to the crank of said last mentioned shaft, a second signalling operating means, means for operatively connecting the second signal operating means with the last mentioned rod 20 and the second one of said shafts of said second mentioned pair being actuatable by the said other operating bar after the first mentioned shaft of said second pair, a crank on said last mentioned shaft of the second 25 pair, and said crank being adapted for engagement with said second catch.

5. In a railroad grade crossing signal, a pair of spaced operating bars actuatable by the wheels of a train, a pair of rock shafts 30 for each operating bar, means operatively connecting the bars and the shafts, a crank on one of the shafts of one of said pair, first operated by one of the bars in the travel of the train on the track, a bar engaged with 35 the crank, means slidably mounting the second mentioned bar, said second mentioned bar having a hole, a signal operating rod, a catch engaged with the rod and engageable with the hole, a signal, signal operating 40 means therefor, means operatively connecting the signal operating means and the rod so that when said one of said operating bars is first engaged by the wheel of the train, said rock shaft is rocked to swing 45 the crank and pull the second bar and rod to cause the operation of the signal, a second catch on the rod, and an abutment with which the second catch is engaged when the rod is pulled, a spring for returning the 50 second catch when the train is off said one operating bar, a second one of the shafts of said pair operated by said one operating bar after operation of said first shaft of said first mentioned pair, one of the shafts of the 55 other pair being actuatable by the other operating bar, a crank on said one shaft of said last mentioned pair, a rod connected to the crank of said last mentioned shaft, a

second signalling operating means, means for operatively connecting the second signal operating means with the last mentioned rod and the second one of said shafts of said second mentioned pair being actuatable by the said other operating bar after the first mentioned shaft of said second pair, a crank on said last mentioned shaft of the second pair, and said crank being adapted for engagement with said second catch, and spring means associated with the operating bars normally holding them in a predetermined 70 position.

6. In a railway grade crossing signal, a pair of spaced bars actuated by the wheels of a train, a pair of rock shafts, each rock shaft of said pair being associated with respective bars, means operatively connecting the bars and the shaft, a crank on one of the shanks, a signal operating rod, means operatively connecting the rod and the crank, a signal, a signal operating means therefor, 80 means operatively connecting the signal operating means and the rod so that when one of said bars is operated, said one shaft is rocked to pull the rod to cause the operation of the signal, a catch on the rod, an 85 abutment with which the catch is engaged when the rod is pulled, means for returning the catch to a disengaged position, and the other of said rock shafts being actuated by the other of said bars, and having a crank 90 thereon to relieve said catch.

7. In a railway grade crossing signal, a pair of spaced bars actuated by the wheels of a train, a pair of rock shafts, each rock shaft of said pair being associated with respective bars, means operatively connecting the bars and the shaft, a crank on one of the shanks, a signal operating rod, means operatively connecting the rod and the crank, a signal, a signal operating means therefor, 95 means operatively connecting the signal operating means and the rod so that when one of said bars is operated, said one shaft is rocked to pull the rod to cause the operation of the signal, a catch on the rod, an 100 abutment with which the catch is engaged when the rod is pulled, means for returning the catch to a disengaged position, and the other of said rock shafts being actuated by the other of said bars, and having a crank 105 thereon to receive said catch, guides associated with said bars and spring means in the bars to hold the guides in normal predetermined position.

In testimony whereof I affix my signature.
WILLIAM J. CARDWELL.
